INVENTOR
ROBERT L. MARSHALL
BY *Wm. H. Marshall*

ATTORNEYS

UNITED STATES PATENT OFFICE.

ROBERT L. MARSHALL, OF ELIZABETHTOWN, KENTUCKY.

WATCH MECHANISM.

No. 921,859.

Specification of Letters Patent.

Patented May 18, 1909.

Application filed September 15, 1908. Serial No. 453,080.

To all whom it may concern:

Be it known that I, ROBERT L. MARSHALL, a citizen of the United States, and a resident of Elizabethtown, in the county of Hardin 5 and State of Kentucky, have made certain new and useful Improvements in Watch Mechanism, of which the following is a specification.

My invention relates to improvements in 10 watch mechanism and more especially to the provision of novel means for mounting the spring, its arbor, spring box with click and winding wheel made integral or attached thereto and the main driving-wheel of the 15 going train, and for retaining the same in position.

The object of my invention, briefly stated 20 is to provide a better, safer, more satisfactory and permanent means of accomplishing the purpose of the above mentioned mechanism 25 than has heretofore been provided in other constructions. I do this in a way that permits jeweling the main driving arbor in permanent jewels set in the main plates at the maximum distance apart, said bearings 30 having less frictional surface than those of other constructions approximating the results I obtain. The spring box of my design has peripheral teeth integral or attached thereto, outside, centrally disposed in relation to, or above or below the center of the 35 depth of the box, said teeth serving in the dual capacity of a click and winding wheel permitting by the construction, the winding of the watch without disturbing the going train or time keeping function of the watch, while winding; the spring box has bearings 40 on itself which keep the novel click and winding wheel in vertical, horizontal and concentric alinement substantially as set forth in the drawings, and following specification. The main arbor in combination with this arrangement has by its greatest possible distance between the jewels, the least possible 45 lateral movement and will permit, for the same reason only the least possible lateral movement or lack of alinement of itself or attached driving wheel, from any possible wear of the bearings, a construction making possible 50 the use of fewer parts than heretofore used, as well as one which if desired can be so made as to accommodate a wider main spring than methods heretofore in use will house.

My invention is also suitable for clocks. 55 The broad subject-matter of this application is shown and described in a co-pending

application Number 453,079 filed September 15, 1908. In the co-pending application a mainspring box or barrel is provided which acts in the dual capacity of a click and winding wheel and the barrel is held in position by means of an annular ring which constitutes part of the peripheral bearings. 60

An object of the invention set forth in the present application is to provide a novel form 65 of means for retaining the spring box in position and for driving the same in its rotary movement.

A further object of the invention is to provide novel means for attaching the main 70 spring to the driving arbor.

Other objects and advantages will appear and be particularly pointed out in the following specification.

My invention is illustrated in the accompanying drawings in which—

Figure 1 is a plan view, partly in section, showing the center wheel, the main driving wheel, and part of the winding mechanism; Fig. 2 is a similar plan view, showing the 80 driving wheel removed, in which the spring box or barrel is held by a cap plate; Fig. 3 is a section taken along the line 3—3 of Fig. 1; Fig. 4 is a section taken along the line 4—4 of Fig. 1; and Fig. 5 is a perspective view of the 85 spring box, the removable collar and the driving wheel.

Referring now to Fig. 1, I have shown therein only so much of the ordinary watch mechanism as is necessary in the explanation 90 of the novel features of my device. These consist of the upper and lower plates A and B respectively, between which are secured the center wheel C, the wheel D, which is a part of the winding train, the driving, and other 95 necessary mechanism.

The manner in which the spring box is mounted is clearly shown in Fig. 3. Disposed in the top and bottom plates in accurate alinement, are the jeweled bearings a, b, 100 respectively. These bearings are permanently secured in the plates and are not intended to be removed. The driving arbor E is journaled in these bearings, which will be noted, are at the maximum distance apart, 105 namely in the top and bottom plates. The driving arbor E has an enlarged portion e upon which is rigidly mounted a driving wheel F. Mounted upon the enlarged portion E of the arbor is a collar C^x which has a central radial extension c provided with a lug c'. The collar C^x has a lower reduced 110

portion c^2 adapted to fit the reduced portion e' of the arbor. The arbor has a longitudinally extending slot e^2 in its enlarged portion and the collar C^x carries a hook for the main spring, said hook extending radially inward through collar and forming a lug which engages in slot e^2 , which thus prevents the arbor turning in the collar and furnishes a means of transmitting the power of the main spring to the going train.

Loosely disposed upon the collar C^x is the spring box G . This consists of a cylindrical casing, provided with the top and bottom pieces g^a and g^b respectively. On the outer circumference of the cylinder there are arranged the teeth H . These teeth may be integral with the box itself or they may be separate from the box and be attached thereto in any suitable manner. In the drawing I have shown these teeth as being arranged in the center of the cylinder but they may be arranged on either side of the center. The main spring J has its outer end attached to the inner side of the spring box, while its inner end is provided with a slot which enables it to be attached to a small hook c' on the collar C^x .

In order to provide guiding and retaining means for the spring barrel the bottom plate B is cut away in the manner shown in Figs. 3 and 4 to provide end and peripheral guides.

In order to hold the movable box in horizontal and vertical alinement and yet reduce the friction to a minimum I have made use of the recesses b' and b^2 in the bottom plate B and the recess b^4 in the cap K . It will be seen that the provision of these recesses leaves peripheral bearing shoulders d' and end bearing shoulders d^2 as clearly shown in the figure. There is a space f below the bottom of the spring barrel to eliminate any possible frictional contact of the bottom of the box with the bottom plate B , except as shown in the drawing.

In order to retain the spring barrel in position, I have provided a cap K which as shown in Fig. 3 surmounts the spring barrel and is provided with the central recess b^4 and the annular groove b^3 heretofore referred to. Between these recesses is the shoulder d^3 which constitutes a peripheral bearing while the inner side of the cap constitutes an end bearing, that portion of the cap toward the center being slightly cored out to just clear the spring box, leaving an engaging portion opposite the outer edge of the box. The shoulders d' , d^2 , d^3 , together with the engaging portion of the cap retain the spring barrel in vertical and horizontal alinement.

The bottom plate B has an upwardly projecting annular flange b^x arranged to fit into the slot b^3 to center the cap and to retain it in its position. The cap K has a laterally extending flange k provided with openings through which the screws L are inserted to

hold the cap securely to the bottom plate B . The space between the recessed cap K and the recessed plate B provides a housing for the spring box while the guide members heretofore referred to permit the rotation of the spring box while holding the same in alinement.

In Fig. 4 I have shown a section of the watch mechanism which includes the driving wheel F which is rigidly secured to the arbor E and is in mesh with the pinion M which in turn drives the center wheel C , and through it the remaining movable parts of the watch.

In winding the watch, the power is conveyed through the wheel D which is in mesh with the teeth H on the spring box G . These teeth are provided with a click or retaining member, and as the wheel D is turned, the power is conveyed through these teeth to the spring box which then revolves in the guide slots formed by the recessed portions in the bottom of the plate B and the retaining cap K as already described. It will be noted that the spring box G is not guided in its movement by the arbor E or by the collar C^x , but is preferably out of contact with the latter and is guided solely by the engaging shoulders b' , b^2 of the bottom plate B and the shoulder d^3 of the retaining cap K . By this construction it will be apparent that there is no frictional wear of the arbor E when the watch is being wound. After and while the watch is wound the tension of the spring J tends to cause the rotation of the collar C^x and through it the arbor E . The movement of the latter turns the driving wheel F and communicates the movement to the other parts of the watch, as before stated.

It will be seen that with the construction herein described, I have provided a spring barrel with click teeth on its periphery, in which the winding may be permitted without any frictional engagement of the arbor with its jeweled bearings. The jeweled bearings themselves are permanently secured in the outer movement plates at a maximum distance apart, thereby providing a maximum stability as far as the lateral movement of the arbor is concerned. Moreover, the arrangement of the retaining cap K , when taken in connection with the bottom plate B provides a bearing for the spring box entirely independent of the other parts of the watch, thus leaving the main driving wheel perfectly free except for the main spring which is connected with the collar and thence with the arbor, to supply the necessary power for driving the wheel. This arrangement also provides means for readily inspecting or repairing the various parts without the necessity of dismantling the watch or removing any of the jewels therefrom. The top plate may be removed and then by simply lifting the drive wheel F the arbor and the drive wheel are withdrawn bodily together from the lower

plate B. By withdrawing the screws L the cap K may be lifted and the collar C^x and the spring box G removed as shown in Fig. 5.

While I have shown the spring barrel as 5 having a top plate g^a and a bottom plate g^b, it will, of course, be obvious that the barrel or box could be made without either one of these or even without both of them since the cylinder is retained in position by means of 10 the guide shoulders, and there is no lateral pressure on either the top or the bottom of the box.

I claim:

1. In a watch or clock mechanism, top and 15 bottom plates, one of said plates being provided with a recess and an annular flange on the edge of said recess, a recessed cap provided with an annular groove arranged to receive said annular flange and a spring box 20 provided with teeth on its periphery arranged to enter the registering recesses of said cap and plate and to be guided by peripheral guide members on said cap and plate.

2. In a watch or clock mechanism, a recessed plate, a rotatable spring barrel carried 25 in said recess and provided with click and winding teeth on its periphery, a grooved cap provided with a laterally projecting flange

arranged to be attached to said plate to retain said spring-box, and centering means 30 carried by said plate on the edge of said recess and arranged to enter said groove.

3. In a watch or clock mechanism, a recessed plate provided with an upwardly extending annular flange on the edge of said 35 recess, a rotatable spring barrel carried in said recess and provided with click and winding teeth on its periphery, a cap provided with an annular groove arranged to engage said flange to guide said cap in position, and 40 means for attaching said cap to said plate.

4. In a watch or clock mechanism, a top plate, a bottom plate provided with a recess, a spring barrel disposed in said bottom plate and provided with teeth on its periphery, a 45 slotted driving arbor journaled in said top and bottom plates, a collar slidably longitudinally of said arbor and having a pin arranged to enter said slot, and a spring arranged within said barrel and having one end 50 attached to said collar.

ROBERT L. MARSHALL.
